(57) **CLAIM**

The ornamental design for a moulding, as shown and described.

DESCRIPTION

FIG. 1 is a perspective view of a moulding showing our new design;

FIG. 2 is an end view thereof;

FIG. 3 is a front view thereof;

FIG. 4 is a bottom view thereof; and,

FIG. 5 is a top view thereof.

The fragmented lines indicate that the moulding continues indeterminately in the direction depicted.
